BY C. P. Gropel

ATTORNEY

UNITED STATES PATENT OFFICE.

ROBERT J. YOHAI AND ROBERT A. YOHAI, OF NEW YORK, N. Y.

DESIGN FOR AN ICE-CREAM CONE.

Application filed March 3, 1925. Serial No. 12,565. Term of patent 3½ years.

To all whom it may concern:

Be it known that we, ROBERT J. YOHAI, a citizen of the Republic of Turkey, residing at 87 Lenox Avenue, in the city, county, and State of New York, and ROBERT A. YOHAI, a citizen of the United States, residing at 56 Lenox Avenue, in the city, county, and State of New York, have invented a certain new, original, and ornamental Design for Ice-Cream Cones, of which the following is a specification, reference being had to the accompanying drawing, forming part thereof.

In the drawing,

We claim:

The ornamental design for an ice cream cone as shown.

ROBERT J. YOHAI.

ROBERT A. YOHAI.
